UNITED STATES PATENT OFFICE.

ROBERT GEORGE McDOWELL, OF WALKERVILLE, MONTANA, ASSIGNOR TO INGERSOLL-RAND COMPANY, OF NEW YORK, N. Y., A CORPORATION OF NEW JERSEY.

OILER.

1,119,522.

Specification of Letters Patent.

Patented Dec. 1, 1914.

Application filed July 12, 1911. Serial No. 638,101.

To all whom it may concern:

Be it known that I, ROBERT GEORGE McDowell, a citizen of the United States, and resident of Walkerville, in the county of 5 Silver Bow and State of Montana, have invented a new and useful Improvement in Oilers, of which the following is a specification.

This invention relates to oilers for direct 10 acting engines, such, for instance, as rock drills, and it has for its object to provide means for feeding oil in very small quantities to the pressure fluid supply for the engine, said feeding means being controlled by 15 vibrations due to the operation of the engine.

A practical embodiment of the invention is represented in the accompanying drawings, in which,

Figure 1 represents the oiler in top plan, 20 Fig. 2 is a front view of the same, Fig. 3 is a section taken in the plane of the line A—A of Fig. 1, a portion of a rock drill being shown to illustrate the location of the oiler with respect thereto, and Fig. 4 is a detail 25 cross section in the plane of the line B—B of Fig. 3.

The rock drill cylinder is denoted by 1, and its valve chest by 2. The pressure fluid supply for the rock drill includes a T-coupling 3, having one branch 4 connected to the valve chest 2, through the pipe 5, and another branch 6 adapted for connection with the main pressure fluid supply pipe 7, and its other branch 8 adapted to receive 35 the casing 9 of the oiler. This casing 9 serves as a reservoir for the oil and it is provided at its outer end with a removable filling cap 10. The inner end of the casing 9 projects into the T-coupling 3 and is preferably tapered so as to give a greater amount 40 of space within the coupling for the passage of the pressure fluid through the coupling. A hollow valve 11 has its hollow stem 12 projecting axially into the oiler casing 9, to a point adjacent to the outer end of the casing. A seat 13 for the valve 11 is provided 45 at the inner end of the casing, the bore of the casing having a cylindrical reduced portion 14 leading inwardly from the valve seat 13 to a slightly enlarged cylindrical portion 15, said enlarged cylindrical portion 15 opening into the oil chamber 16. A valve seat 17 is provided where the chamber 16 communicates with the portion 15 of the bore and a normally open auxiliary valve 18

is provided on the hollow valve stem 12 in position to limit the opening movement of the valve 11 and close communication from the oil chamber 16. A nut 19 locks the valve 18 in position. A coil spring 20 is interposed 60 between the valve 18 and the interior annular shoulder 21 at the juncture of the portions 14 and 15 of the bore of the casing, which spring serves to hold the valve 11 normally closed and the valve 18 normally 65 open. Open communication is established from the oil chamber 16 to the valve seat 13, in the present instance, by flattening the sides of the valve stem as shown at 22.

Proceeding to describe the operation of 70 the oiler: The hollow valve 11 and valve stem 12 permit the pressure fluid to pass therethrough and exert its pressure on the top of the oil within the chamber 16. When the engine is in operation, the vibrations of 75 the engine will shake the valve stem 12 sufficiently to open the valve 11 slightly and thus permit the oil to pass therethrough in small quantities but uniformly, into the pressure fluid supply passing to the engine. This is 80 readily accomplished by reason of the long valve stem which is readily vibrated by the vibrations of the engine, the closing spring 20 for the valve 11 being adjusted to the required tension to permit more 85 or less quantities of oil to pass through the valve 11, the weaker the tension of the spring 20, the more freely will the oil pass through the valve 11. The auxiliary valve 18 limits the opening movement of the oil 90 distributing valve 11 and also closes the inner end of the oil chamber 16 when the valve 11 is at the limit of its movement away from its seat 13. This oiler can be used in 95 any position from vertical to horizontal.

While I have shown this oiler in connection with a rock drill, it is to be understood that I do not wish to limit myself to the particular application shown and described herein but contemplate its use in connection 100 with the pressure fluid supply for engines of various characters.

What I claim is:

1. In an oiler for pressure fluid operated tools having a fluid supply pipe, a closed oil reservoir having an oil supply passage leading to said fluid supply pipe, a hollow valve for said passage having a hollow valve stem affording communication between said fluid supply pipe and said oil reservoir and 105 110

- 2
- a spring for resiliently closing said valve, the said spring being of slight tension to permit the opening of said valve from the vibration of said tool.
  - 5 2. In an oiler for pressure fluid operated tools having a fluid supply pipe, a closed oil reservoir having an oil supply passage leading to said fluid supply pipe, a hollow valve for said passage having a hollow valve
  - 10 stem affording communication between said fluid supply pipe and said oil reservoir, a spring for resiliently closing said valve, the said spring being of slight tension to permit

the opening of said valve from the vibration of said tool, and an auxiliary valve on said valve stem for limiting the opening movement of the first named valve and closing the said passage.

In testimony, that I claim the foregoing as my invention, I have signed my name in 20 presence of two witnesses, this twenty eighth day of June, 1911.

ROBERT GEORGE McDOWELL.
